UNITED STATES PATENT OFFICE.

ROBERT GALBRAITH AND EDWARD AMBROSE, OF TROY, NEW YORK, ASSIGNORS TO GREAT WESTERN STOVE COMPANY, OF LEAVENWORTH, KANSAS.

DESIGN FOR A STOVE.

No. 38,840.

Specification for Design.

Patented Sept. 24, 1907.

Application filed July 17, 1907. Serial No. 384,289. Term of patent 7 years.

To all whom it may concern:

Be it known that we, ROBERT GALBRAITH and EDWARD AMBROSE, of the city of Troy, county of Rensselaer, and State of New York, have invented a new, original, and ornamental Design for Stoves, of which the following is a specification, reference being had to the accompanying drawing, forming part thereof.

Figure 1 is a side view of a stove, showing my new design, and Fig. 2 is an end view.

I claim
The ornamental design for a stove, as shown.

ROBERT GALBRAITH.
EDWARD AMBROSE.
